(57) **CLAIM**

The ornamental design for a door for a wheeled work machine cab, as shown and described.

DESCRIPTION

FIG. 1 is a front perspective view of a door for a wheeled work machine cab embodying our new design;
FIG. 2 is a front elevational view thereof;
FIG. 3 is a left side elevational view thereof;
FIG. 4 is a rear elevational view thereof;
FIG. 5 is a right side elevational view thereof;
FIG. 6 is a top plan view thereof; and,
FIG. 7 is a bottom plan view thereof; the dotted line representations are for illustrative purposes only and form no part of the claimed design.

1 Claim, 3 Drawing Sheets

FIG. 1

FIG._3**FIG._2****FIG._6**

FIG. 4**FIG. 5****FIG. 7**
